UNITED STATES PATENT OFFICE.

JASPER LEOPOLD GREENWOOD, OF NORTH EAST HARBOR, NOVA SCOTIA, CANADA.

RIM CONTRACTOR AND EXPANDER.

Application filed September 15, 1923. Serial No. 662,924.

To all whom it may concern:

Be it known that I, JASPER L. GREENWOOD, a citizen of the United States, and a resident of North East Harbor, Nova Scotia,

5 Canada, have invented a new and Improved Rim Contractor and Expander, of which the following is a full, clear, and exact description.

This invention relates to a tool for contracting and expanding split rims for automobile tires, and has for an object the provision of a simple, efficient and durable device which can be very easily operated to effect the certain and ready contraction and 15 expansion of a split rim.

Another object concerns the provision of auxiliary means whereby the interengaging lock members on the rim sections can be simply and easily disengaged and reengaged as 20 desired.

The invention is illustrated in the drawings, of which—

Figure 1 is a side elevation of a portion of a rim with the tool applied thereto in the 25 position which the parts assume when the rim has just been expanded into its normal position;

Fig. 2 is a partial elevation of the parts in their positions when the rim has been contracted;

Fig. 3 is a section on the line 3—3 of Fig. 1; and

Fig. 4 is a section on the line 4—4 of Fig. 1.

35 The form of the invention shown in the drawings is a preferred form, although it is understood that modifications in the construction and arrangement of the parts and in the character of the materials used may 40 be adopted without departing from the spirit of the invention.

In the general contemplation of the invention, I have desired to provide a pair of rim-clamping members suitably interconnected by links and levers and associated with an auxiliary lever on which is a rim-engaging finger, which finger is adapted to be associated with the rim at a point closely adjacent the split therein so that in the movement of the levers the auxiliary lever is so operated as to cause the engagement of the finger at this point to more certainly lift the lock or latch plate on the end of one section of the rim out of engagement with the other and to more certainly reengage them when the rim is being expanded. Furthermore,

the invention includes the provision of simple and efficient means for locking the parts in either of their positions as the rim is fully expanded or fully contracted. 60

As shown in the drawings, the invention concerns the provision of a tool to be applied to a split rim, the ends of which are numbered 1 and 2 and abut each other along the line 3. One of said sections, preferably 2, 65 is provided with a locking plate 4 having a dependent hook 5 extending into an aperture in the other section 1, this section 1 being provided with a movable latch plate 6 which extends over the aperture to retain 70 the hook therein. This construction is one of the well known forms of construction for split rims. Adjacent the split 3, although not necessarily very close thereto, are rim-engaging clamping elements 7 and 8 of any 75 suitable type. To one of said elements, 7, a lever 9 is pivoted. To the other of said elements, 8, a link 10 is pivoted. The other end of this link is pivotally connected to a point intermediate the length of the lever 9. 80

To a point intermediate the length of the link 10 an auxiliary lever 11 is pivoted. On the inner end of this auxiliary lever is pivotally mounted a rim-engaging finger 12. To this finger a spring 13 is connected, the other end of which spring is connected to the auxiliary lever 11 and, therefore, tends to swing the finger around to the position shown in dotted lines in Fig. 1, or a similar position on the opposite side of the end of 90 the lever 11.

A locking bar 14 is pivotally engaged with the inner end of lever 9, and the other end of it is provided with a hook 15 adapted to be engaged in any one of a plurality of apertures such as 16 in the link 10 so as to hold this link and the co-operating parts in a definite position after these parts have assumed that position. By providing more than one aperture such as 16 in the link 10, 100 the parts may be locked in more than one position. The outer end of the auxiliary lever 11 is provided with a locking bar 17 which is adapted to be engaged in a hole in the lever 9 for the purpose of lockingly 105 relating the end of the auxiliary lever 11 with respect to the position of lever 9 so that the movement of lever 9 will cause the movement of lever 11 when they are locked together. 110

In the operation of the device, assuming that the parts are in the positions shown in

Fig. 1, it will be noticed that the finger 12 is engaging the latch plate 6 and that said plate has been moved transversely of the rim to move it from over the aperture in which the finger or hook 5 lies. The lock bar 17 is connected between the levers 9 and 11, but the lock bar 14 is disengaged. Then the lever 9 is moved to the dot-and-dash position shown in Fig. 1, which will cause the lever 11 to move to a corresponding dot-and-dash position, and through this movement the end of the finger 12 will act as a sort of fulcrum for the lever 11 and enable the end of the section 2, including the latch plate 4, to be sharply drawn away from the end of the other section. In other words, the end of the finger 12 tends to keep the end of section 1 in a fixed position while the movement of the linkage is causing the movement in the end of the other section. After the operation of the device has completely removed the end of one section from the end of the other, then the parts are locked until the reverse operation is desired, when by merely unlocking the bar 14 and moving the parts back to the position shown in full lines in Fig. 1, the end of section 2 is permitted to assume its normal position with respect to the end of section 1, and

while this takes place the end of section 1 is held in a relatively fixed position by the end of finger 12.

What I claim is:—

1. In a rim contractor and expander, the combination of coacting clamps to detachably engage the rim adjacent the split therein, a lever pivoted to one of said clamps, a link bar pivoted at one end to said lever and at the other end to the other of said clamps, an auxiliary lever pivoted to said link bar, and a rim-engaging finger on the inner end of said auxiliary lever to engage the rim closely adjacent the split therein.

2. In a rim contractor and expander, a combination of coacting clamps to detachably engage the rim adjacent the split therein, a lever pivoted to one of said clamps, a link bar pivoted at one end to said lever and at the other end to the other of said clamps, an auxiliary lever pivoted to said link bar, a rim-engaging finger on the inner end of said auxiliary lever to engage the rim closely adjacent the split therein, and a lock bar adjustably connectible between the first-mentioned lever and the rear end of the auxiliary lever to lock them together when desired.

JASPER LEOPOLD GREENWOOD.
